Primary Examiner — Christy Nemeth(74) *Attorney, Agent, or Firm* — ICE MILLER LLP;
Justin D. Swindells(57) **CLAIM**

The ornamental design for charging station for electric vehicles as shown and described.

DESCRIPTION

FIG. 1 is a perspective view showing my new design;
FIG. 2 is a front view thereof;
FIG. 3 is a left side view thereof;
FIG. 4 is a right side view thereof;
FIG. 5 is a back view thereof;
FIG. 6 is a top view thereof; and,
FIG. 7 is a bottom view thereof.
